UNITED STATES PATENT OFFICE.

JAMES S. MASSEY, OF TOLEDO, OHIO.

CARD OR MIRROR HOLDER AND LIGHTING DEVICE.

Application filed December 28 1925. Serial No. 77,964.

To all whom it may concern:

Be it known that I, JAMES S. MASSEY, a citizen of the United States, and a resident of Toledo, in the county of Lucas and State of Ohio, have invented a new and useful Card or Mirror Holder and Lighting Device, which invention is fully set forth in the following specification.

This invention relates to plate or card holders, and particularly to a combined mirror and lamp holder, for use in connection with counter scales to display to customers the weight and other readings indicated on the front of the scale.

The object of the invention is the provision of a novel holder of the character described that is simple and inexpensive to manufacture, light and durable in its construction and combines a holder for a card or mirror, brackets for electric lamps to eliminate the same and an enclosed channel or conduit for the lead wires to the lamps, all preferably formed from a single piece of sheet material.

The invention is fully described in the following specification, and while in its broader aspect it is capable of embodiment in numerous forms, a preferred embodiment thereof is illustrated in the accompanying drawings, in which,—

Figure 1 is an end elevation of a holder embodying the invention carried in operative relation to a scale, the upper portion only of which is shown. Fig. 2 is a front elevation thereof. Fig. 3 is a perspective fragmentary view of the holder before the bracket members for the lamps are bent into lamp carrying position. Fig. 4 is a similar view with a mirror plate, partly broken away, in position in the holder and with the lamp carrying bracket in lamp carrying position, and Fig. 5 is a similar view with the lamp attached to the bracket.

Referring to the drawings, 1 designates the top portion of a counter scale or other device, the front or indicating portion of which is desired to be viewed from the rear, and 2 a rod or bracket arm rising therefrom and carrying a holder 3 for a mirror plate 4 in position for the reflection in the mirror of the indicating portion of the scale to be read from the rear.

The holder 3 in which the invention resides has an adjustable connection 5 with the rod 2, as is common in devices of this character. The holder itself preferably

comprises a single strip of sheet metal, or other suitable sheet material, which forms a backing for the mirror plate 4 and has its upper and lower edges doubled over in 60 spaced relation to the holder plate body to form retaining flanges 6 for the mirror plate 4, card or other device that is intended to be carried by the holder. The member 4 may be slid into holding engagement with the holder from either end thereof.

The holder plate is rearwardly looped or shaped, substantially centrally between its upper and lower edges and throughout 70 its length, to form a channel 7 which opens toward the mirror plate 4 and is, therefore, closed at its open side by said plate. The rear wall or closed side of the channel 7 is provided at each end with an integral 75 tongue or extension 8 of a width corresponding to the width of the channel and adapted to be bent forward with respect to the mirror plate 4 at right angles thereto so as both to close the adjacent end of the channel 80 7 and to form a bracket which projects in advance of the plate 4 for carrying an electric lamp socket 9. The brackets 8 for this purpose are each provided near the outer end thereof with an opening 10 for receiving 85 the insulated holding member 11 of the socket. The lead wires 12 for the socket are intended to project through the member 11 and thence pass into the adjacent end of the channel 7 through an opening 13 in the 90 bracket. The wires extend through the channel 7 to a point where they may extend through a side opening 14 in the channel and lead to any desired point.

It is apparent that the mirror holder embodying my invention comprises a single piece of sheet metal or other suitable material, the upper lower edges of which are fastened to slidably embrace the respective edges of the mirror plate and that the holder 100 is formed to provide a channel for the lamp wires and also to provide integral tongues forming brackets for the lamps, and that such tongues in addition to carrying the lamps also hold the mirror in position with- 105 in the holder.

I wish it understood that my invention is not limited to any specific construction, arrangement or form of the parts, as it is capable of numerous modifications and 110 changes without departing from the spirit of the claims.

Having thus described my invention, what I claim as new and desire to secure by Letters Patent is:

1. A mirror plate holder comprising a single piece of sheet metal having angled upper and lower edge portions for engaging and holding a mirror plate, a rearwardly pressed portion to form a lengthwise extending wire receiving channel, and an integral tongue at each end of the channel forwardly angled to close the adjacent channel end and form a lamp support in advance of the holder.
2. A holder of the class described comprising a single strip of sheet material having provision at its upper and lower edges for engaging and holding a mirror plate and being looped longitudinally thereof to form a wire receiving channel, the open side of which is adapted to be closed by a mirror plate carried by the holder, the ends of the bottom wall of the channel being extended to form tongues adapted to be bent forwardly to close the ends of the channel and to project forwardly of the holder, said tongues having openings for receiving and holding the lamp socket, and wire receiving openings in register with the channel.
3. In combination, a plate-like member, a holder therefor formed of a single piece of sheet material and having upper and lower edges forming slideways for receiving and holding the respective edges of said

member, said holder material being rearwardly looped to form a wire receiving channel throughout the length of the holder and having integral tongues projecting from the ends of the bottom wall of the channel and being bendable at right angles to said member to project forwardly beyond the same, 40 said tongues being adapted to carry electric lamps and having provision for the extension of the lamp lead wires therethrough into said channel.

4. In combination, a mirror plate, a holder for said plate comprising a single strip of sheet metal with its upper and lower edges fashioned to form retaining slideways for the respective edges of said plate and being shaped intermediate the said edges to form a channel lengthwise of the holder, the open side of which is closed by the mirror plate, the rear or bottom wall of the channel having integral tongues projecting from the ends thereof and bendable forwardly at the ends of and beyond the face of said plate to close the respective channel end to hold the plate in position in the holder and to form a lamp bracket, said tongues being perforated for the extension of lamp lead wires 60 therethrough into and lengthwise of said channel and said channel having an opening intermediate its ends for the lead wires.

In testimony whereof I have hereunto signed my name to this specification.

JAMES S. MASSEY.
